UNITED STATES PATENT OFFICE.

DANIEL F. UPDEGRAFF, OF IRWIN, PENNSYLVANIA.

POTATO-SEPARATOR.

SPECIFICATION forming part of Letters Patent No. 615,325, dated December 6, 1898.

Application filed October 7, 1897. Serial No. 654,456. (No model.)

To all whom it may concern:

Be it known that I, DANIEL F. UPDEGRAFF, a citizen of the United States, residing at Irwin, in the county of Westmoreland and 5 State of Pennsylvania, have invented a new and useful Potato-Separator, of which the following is a specification.

This invention relates to machines for cleaning and assorting potatoes and like vegetables, 10 the principal object being the provision of a machine easy of operation, light and compact in its structural arrangement, comprising a minimum number of parts, and accessible for cleaning or any required purpose.

15 For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof 25 is shown in the accompanying drawings, in which—

Figure 1 is a perspective view of a separator constructed in accordance with this invention. Fig. 2 is a side elevation, the near 30 side of the hopper and body being removed and the stanchions being in section. Fig. 3 is a section on the line X X of Fig. 2, looking in the direction of the arrow. Fig. 4 is a view of the machine as seen looking at the delivery 35 end. Fig. 5 is a section on the line Y Y of Fig. 2, looking in the direction of the arrow. Fig. 6 is a section on the line Z Z of Fig. 2, viewed in the direction of the arrow. Fig. 7 is a transverse section of a side portion of 40 the hopper on a larger scale.

Corresponding and like parts are referred to in the following description and indicated in the several views of the accompanying drawings by the same reference characters.

45 The framework comprises end stanchions 1 and 2, similarly constructed and formed of bars or legs crossing between their ends and secured together at the point of crossing. Longitudinal bars 3 connect corresponding 50 legs below their point of crossing, and other bars 4 join the upper ends of the said legs. Braces 5 are interposed between the upper

and lower portions of the legs to stiffen and strengthen them and extend from the longitudinal bars 4 to the adjacent longitudinal 55 bars 3 to form means of attachment therewith of the fabric 6, inclosing the upper portion of the frame and providing sides therefor, said fabric being secured at its upper edge to the bars 4, at its lower edge to the 60 bars 3, and at its ends to the braces 5. The space inclosed by the sides 6 flares at its upper end and is contracted at its lower end to direct the potatoes or other articles into a suitable receptacle 7 placed beneath the 65 separator for their reception.

A hopper 8 is provided at the receiving end of the separator and consists of upwardly-divergent sides 9, secured to the end portions of the bars 4 projecting beyond the stanchion 70 2, and an end piece 10. An arched bar 11 connects the upper ends of the legs forming the stanchion 2 and in conjunction with the braces 5 prevents spreading thereof. A grate 12 forms the bottom of the hopper and inclines downwardly toward its inner end and is composed of a series of longitudinally-disposed slats secured to transverse bars and is held in place by flexible strips 13 of fabric or like material, secured at their longitudinal 80 edges to the sides 9 and longitudinal edge portions of the grate 12. These flexible strips 13 admit of the grate 12 having a limited vertical movement and close the spaces formed between the sides of the hopper and the edges 85 of the grate, so as to prevent potatoes or other matter lodging therein and interfering with the free vertical movements of the grate, which are essential to the proper feed of the potatoes to the separating-barrel. By reason 90 of the upward and outward inclination of the sides 9 it will be understood that when the grate 12 moves upward spaces will be formed between its longitudinal edges and the said sides 9, and should potatoes or other matter 95 enter the spaces the grate would not be permitted to return to its normal position, and to obviate this objection the flexible strips 13 have been provided and applied in the manner set forth.

100 The separating-barrel 14 is of polygonal form in cross-section and is composed of a series of slats or boards grouped about a central line and having their longitudinal edges

touching, the inner flattened sides serving to thoroughly agitate the potatoes when the barrel is in motion, thereby securing better results than if the interior of the barrel were 5 circular. A ring 15 is at the receiving end of the barrel, and the adjacent ends of the slats are secured thereto, and a series of tappets 16 are applied to the outer face of the ring and consist of short strips obliquely disposed, so 10 as to engage with a projection 17, pendent from the inner end of the grate 12, whereby the latter has a vertical reciprocatory movement imparted thereto at its inner end. A ring 18 is applied to the rear or delivery end 15 of the barrel, and the contiguous ends of the slats are secured thereto, and a plate 19, arranged parallel with and at a short distance from the ring 18, is connected thereto by pins 20, the space between the parts 18 and 19 20 forming an egress for the potatoes or articles not passing through the perforations in the slats comprising the separating-barrel. This space is just large enough to admit of the discharge of the potatoes without permitting the 25 barrel to become empty, which is of advantage in the separating process, as the potatoes are retained in the separator for a longer period of time, thereby insuring a thorough separation and cleaning. A disk 21 is applied to 30 the outer face of the plate 19 and is of less diameter and constitutes a journal or rotat- ing support for the delivery end of the barrel and rests in the crotch formed between the upper ends of the legs of the stanchion 1. 35 The marginal portion of the plate 19 engages with the inner faces of the legs 1 and prevents outward movement of the separating-barrel. Rollers 22, journaled longitudinally between the upper ends of the legs 2 and bars 23, con- 40 nected therewith, support the ring 15 and the receiving end of the barrel 14.

The separating-barrel 14 inclines downwardly toward its outer or delivery end, whereby the potatoes or other articles to be sepa- 45 rated are fed therethrough by gravity, and this barrel is rotated in any convenient way, and, as shown, a crank 24 is secured to a block applied to the disk 21. A vertical partition 25 is located at the delivery end of the 50 barrel and beneath it and serves to separate the smaller potatoes from the larger, and an opening 26 is provided in a side of the body opposite the space formed in the rear of the partition 25, and a chute 27, extending across 55 the lower end of this space, directs the larger potatoes through the side opening 26 into a receptacle 28 placed to receive the larger potatoes or articles as they escape from the machine. An inclined chute 29 is placed be- 60 neath the inner portion of the separating-barrel and receives the potatoes dropping therefrom and directs them to a contracted space above the receptacle 7, thereby pre- 65 venting the potatoes dropping from the upper or inner portion of the barrel onto the ground.

The potatoes or articles to be cleaned and

separated are dumped into the hopper 8 upon the grate 12, and the separating-barrel is rotated at the required speed and imparts a 70 jiggling or vertical reciprocating movement to the inner end of the grate 12, whereby the potatoes are agitated and caused to enter the barrel, the smaller potatoes escaping through the openings in the sides thereof and the 75 larger potatoes passing through the barrel and escaping through the space formed between the parts 18 and 19, as set forth herein.

Having thus described the invention, what is claimed as new is—

1. In a potato-separator, the combination of a fixed hopper, a grate constituting a movable bottom for the hopper and having a pendent projection at and beneath its delivery end, flexible strips connecting the edge portions of the grate with the sides of the hopper, a rotary separator-barrel disposed to receive the potatoes from the grate and having a flange extending around the exterior of the receiving end of the barrel and partly closing the discharge end of the hopper, and a series of strips obliquely disposed and secured to the face of the flange adjacent to the hopper and adapted to engage with the pendent projection of the grate and reciprocate the latter vertically as the separating-barrel is rotated, substantially as described for the purpose set forth.

2. In a potato-separator, the combination of an end stanchion composed of crossing bars, a hopper supported in the upper crotch of one of the stanchions and provided with a movable bottom in the form of a grate, and a separating-barrel having an exterior circumferential flange provided at the receiving end 100 of the barrel, rollers secured to the upper ends of the respective end stanchion forming a bearing for the receiving end of the barrel, and the other end of the barrel having a circumferential flange provided upon its outer 105 face with a disk, said disk fitting in the crotch of the other stanchion and forming a journal for the discharge end of the barrel, and obliquely-disposed strips attached to the flange upon the receiving end of the barrel to engage with the movable bottom of the hopper, sub- 110 stantially as shown and described.

3. In a potato-separator, the combination of end stanchions formed of crossing legs, upper and lower longitudinal bars connecting corresponding legs opposite their point of crossing, braces spanning the angles formed between crossing legs and extending from upper to lower longitudinal bars, upwardly-di- 120 vergent flexible sides secured at their ends to the said braces and at their upper and lower edges to the longitudinal bars, and a separat- 125 ing-barrel inclining downwardly toward its delivery end and rotatably mounted at its lower end in the upper crotch of a stanchion and at its upper end to the other stanchion opposite the crotch, substantially as and for the purpose set forth.

4. The herein-described separator for po-

tatoes, comprising end stanchions formed of crossing legs, upper and lower longitudinal bars connecting corresponding legs of the stanchions, the upper bars projecting at one end beyond a stanchion, braces connecting the legs upon opposite sides of their point of crossing and extending from the upper to the lower longitudinal bars, flexible sides secured to the braces and longitudinal bars, one of the sides having a discharge-opening at its lower rear end, a chute extending transversely from the opposite side to the lower portion of the said discharge-opening, a vertical partition at the inner side of the chute, a hopper at one end of the separator and secured to the projecting ends of the upper longitudinal

bars, a grate forming a bottom to the hopper and connected thereto at its edges by flexible strips, a separating-barrel journaled at its ends to the stanchions, a chute beneath the inner portion of the barrel, and tappets applied to the upper end of the separating-barrel to engage with and vertically reciprocate the aforesaid grate, substantially in the manner and for the purpose specified. 25

In testimony that I claim the foregoing as my own I have hereto affixed my signature in the presence of two witnesses.

DANIEL F. UPDEGRAFF.
